CABLE WRAPPING MACHINE

Stanley Forrest French, Dobbs Ferry, and Ernest Louis Junghanns, Yonkers, N. Y., assignors to Anaconda Wire & Cable Company, New York, N. Y., a corporation of Delaware

Application July 9, 1932, Serial No. 621,568

8 Claims. (Cl. 117—41)

This invention relates to mechanism for wrapping tape, strips, cords and the like around conductors, cables, cores and the like and more particularly to wrapping mechanism of the so-called planetary type wherein relative motions of longitudinal advance and planetary revolution are given to the cable and tape respectively.

One of the objects of the present invention is to provide an improved wrapping machine of the planetary type.

Another object of the present invention is to provide an improved means to supply the wrappings from the unwinding roll of tape, strip, cord or the like to a conductor, cable or the like at a substantially constant tension.

Another object of the present invention is to facilitate the wrapping of conductor, cable or the like with tape, strip, cords and the like.

Another object of the present invention is to provide improved tape roll supporting means wherein means are provided to permit ready and quick removal and replacement of the roll, means are provided to accommodate successive rolls of variable widths as desired, means are provided to permit the roll to rotate freely about its center axis and friction brake means are provided to supply the unwinding tape to tensioning means intermediate the roll and cable at a substantially constant tension at all tape roll diameters.

Other objects and advantages will be apparent as the invention is more fully disclosed.

In wrapping machines of the planetary type it is customary to provide means to sustain a cable in a straightaway course, means to support one or more tape rolls adjacent the course, and means to impart to the cable and tape roll relative motions of longitudinal advance and of planetary revolution. It is customary to rotatably support the roll upon a suitable head or frame rotatable about the cable as an axis, and to provide a tensioning device between the cable and tape roll to maintain a desired tension in the tape as it is wrapped upon the cable. It is also customary to provide guide means to apply the tape to the cable substantially free from lateral restraint.

In copending application entitled Tape tensioning means, Ser. No. 613,377, filed May 25, 1932 by Stanley Forrest French, one of the co-inventors of the present invention is disclosed an improved type of tape tensioning means wherein electrically controlled means are utilized to maintain a substantially constant tension in the tape being wrapped upon the cable. The tape tensioning means of this copending application essentially comprises a drum operatively connected with an electric motor to be driven thereby in one direction and means to pass the tape from a tape roll over the drum and to the cable so that the said tape frictionally engages the drum surface

substantially as a belt to drive or rotate the drum in a direction reverse to that in which the drum is driven or rotated by the motor. Circuit control means are provided to regulate the speed of rotation of the drum by the motor to obtain a desired tension in the tape as it leaves the drum to pass to the cable. This copending application is assigned to the same assignee as the present invention.

In copending application entitled Tape guide means for planetary taping machines, Ser. No. 621,064, filed July 6, 1932 by Ernest Louis Junghanns, one of the co-inventors of the present invention is disclosed an improved guide means to apply the tape to the cable substantially free from lateral restraint. The tape guide means of this copending application comprises essentially a pair of spaced cylindrical roller members over which the tape passing from the tape roll of the planetary taping machine to the cable is passed before being fed to the said cable. One of the rollers is swivelly positioned upon the rotating taping head of the planetary taping machine in relative close spaced relationship to the cable course with its longitudinal rotating axis lying in a plane substantially parallel to the longitudinal axis of the cable, and the other roller is supported upon the taping head with its longitudinal rotating axis lying in a plane parallel to the longitudinal axis of the first roller at such a spaced distance therefrom as is adapted to eliminate substantially all lateral stresses and strains in the tape as are incident to the swiveling of the first roller. This copending application also is assigned to the same assignee as the present invention.

In accordance with the objects of the present invention, when the two inventions of these copending applications are combined in wrapping machines of the planetary type it has been found necessary to redesign the machine to permit their cooperation and to obtain certain operating benefits arising therefrom, and to also provide improved tape roll supporting means and an improved means to supply the unwinding tape from the roll to the tensioning means at a substantially constant tension at all tape roll diameters, all as will be more fully hereinafter disclosed.

Before further disclosing the present invention reference should be made to the accompanying drawings wherein—

Fig. 1 is a perspective schematic view of the planetary taping machine of the present invention;

Fig. 2 is a sectional view of the same; 55
Fig. 3 is an enlarged section of a single taping head disclosing the relative positioning of the elements comprising the same;

Fig. 4 is an enlarged section of the tape roll supporting means and variable tape roll friction 60

means to feed the unwinding tape to the electrically controlled tape tensioning means at a substantially constant tension independently of the tape roll diameter;

5 Fig. 5 is a sectional view of the variable tape roll friction means along plane 5-5 of Fig. 4; and

6 Fig. 6 is an enlarged sectional view along plane 6-6, Fig. 4.

10 Referring to the drawings, the planetary taping machine described is one designed to permit the simultaneous application of a plurality of wrappings upon a single cable if desired. As shown, the machine comprises a spider 2 rotatable about 15 its center longitudinal axis 3 at which axis is disposed cable 4. Means (not shown) are provided to impart relative motions of longitudinal advance and planetary revolution to cable 4 and spider 2 respectively. This means has heretofore 20 been employed in the art.

Upon spider 1 are disposed a plurality of taping heads 1, each head being located at substantially the same radial distance from the rotating axis of the spider 2 and each head is spaced from an 25 adjacent head along the spider frame with each succeeding taping head in a different quadrant, as is schematically shown in Fig. 1. The relative spacing between each adjacent taping head may be made as small as the mechanism of each 30 taping head will permit. Each taping head 1 includes a suitable frame identified by numeral 1 supported on the spider frame 2, a tape roll 5 mounted on an anti-friction bearing 6 and friction means 7-7' to supply the unwinding tape 35 5' from the roll 5 to a tape tensioning means 8 at a substantially constant tension at all diameters of the tape roll.

Tape tensioning means 8 is preferably of the 40 type disclosed and claimed in copending application Ser. No. 613,377 to Stanley Forrest French above identified, and briefly comprises a rotatable drum (identified by numeral 8) over which tape 5' passes, means 9 to maintain tape 5' constantly in non-slipping frictional engagement 45 therewith, and means to rotate drum 8 in a direction opposite to the direction of rotation induced by tape travel thereover, said means comprising a variable speed electric motor (not shown) and an electric circuit therefor (also not shown) including means to control the current input to the 50 said motor to obtain a desired reverse rotation of the said drum 8. By thus placing a regulable reverse torque on drum 8 resisting the turning of the drum incident to tape 5' passing thereover 55 a desired tension in tape 5' may be obtained between drum 8 and cable 4.

From the tape tensioning means 8, tape 5' passes over a tape guide means to cable 4. The 60 tape guide means disclosed in the drawings is substantially the guide means disclosed and claimed in copending application Serial No. 621,064 to Junghanns above identified and comprises cylindrical rollers 10 and 11 mounted upon taping head 1 to rotate therewith. Roller 11 is positioned closely adjacent the cable course of cable 4 with its rotating longitudinal axis lying substantially parallel thereto, and is of the type known in the art as a caster or swivel roller, being adapted to swivel about its center transverse axis as well as to freely rotate about its 65 longitudinal axis. Roller 10 is positioned in relatively close spaced relationship to roller 11 with its longitudinal rotating axis parallel to the longitudinal rotating axis of roller 11, the spacing 70 between the rollers being adapted to eliminate 75

lateral stresses and strains from the tape incident to the swiveling of roller 11. In this arrangement of guide means a self-adjusting angle of lay is obtained in the tape 5' as it passes from roller 11 to cable 4 by means of the swivel mounting of roller 11 without placing on the tape any lateral stresses and strains tending to break the tape 5'. To provide for the taking up of slack in tape 5' as it passes over guide rollers 10 and 11, roller 10 is provided with a spring 37 operating to maintain roller 10 in frictional engagement with tape 5' as it passes thereover.

In copending application to Stanley Forrest French above identified, means were disclosed to supply tape 5' to the electrically controlled tape tensioning means 8 at a substantially constant tension independent of tape roll diameter.

Briefly, such means comprised a friction roller supported on the frame 1 by means of a pivoted lever arm and adapted to rest upon the unwinding 20 face of the tape roll. Spring tensioning means were provided to maintain the friction roller in constant contact with the unwinding surface of the roll as the diameter of the roll decreases. It is found that this means while operative to obtain 25 the result desired, permitted the unwinding tape to bulge up just behind the friction roller. To eliminate this feature the means 7-7' of the present invention was devised.

Means 7-7', which may hereinafter be identified as pad friction means, is designed to give approximately constant tension in the tape leaving the pad as the pad decreases from maximum diameter to minimum diameter. Pad friction is also necessary to prevent the pad from overrunning when the machine is stopped. As above disclosed the pad center is mounted upon antifriction bearings 6 to eliminate all possible friction at 30 this point because this friction would vary with changing centrifugal force, thereby causing varying tension in the unwinding tape due to decreasing pad radius and pad weight as the pad is unrolled. It is necessary, therefore, when an antifriction bearing is used to apply friction to the 35 pad which will automatically vary with the decreasing pad radius to maintain a determined or desired tension in the unwinding tape as it passes to tape tensioning means 8.

Briefly stated, the present pad friction means comprises a series of spring fingers 13 disposed upon parallel spaced arms (identified by numerals 7-7') radiating from the pad center supporting means, which fingers are adapted to frictionally engage the pad along its entire radius on each side of the pad. The fingers are arranged upon the arms 7-7' so that they successively lose contact with the pad as the pad radius decreases, thus progressively reducing the frictional torque but maintaining substantially the same pull on the tape (within relatively small limits). 50 Mathematical determination of the spacing of the friction springs shows that a large proportion of the friction must be located near the center of the pad due to the fact that the tension in the tape is at all times equal to the total retarding torque divided by the pad radius. It is necessary, therefore, to dispose the spring fingers 13 so that as the pad radius decreases the release of the pad friction means is proportioned to retain a relatively large proportion of the same 55 about the pad center.

There are many ways in which this may be accomplished. In the drawings, the method disclosed is to increase the number of spring fingers 13 towards the center of the pad, as long as is 60 65 70 75 80 85 90 95 100

practical and to provide friction ring members 15 and 15' adjacent the pad center in place of a plurality of the spring fingers. Friction ring 15 is held against the pad center by coil springs 16.

5 The friction ring is designed to give a larger friction area than an equivalent number of spring fingers and the springs 16 are adjustable to give any desired frictional engagement of the ring to the pad. The friction rings 15-15' also tend to

10 hold the pad in a vertical plane.

In the planetary taping machine of the type described as has been heretofore disclosed it is necessary to mount the tape pad 5 upon an anti-friction bearing 6 in order to eliminate variable

15 friction at this point. It is also necessary to provide means to readily remove and replace the tape pad 5, and to adapt the tape pad mounting to receive pads of variable widths (within certain limits) and to further provide means to adjust

20 the mounting so that for all pads of different widths, the pad center line A (Fig. 4) falls in the line of rotation of the rotation axis of the caster guide roller 11.

To accomplish these desired results we have 25 designed the pad mounting disclosed in section in Fig. 4 wherein the tape pad 5 is mounted upon an anti-friction (ball-bearing) hub 20 which in turn is mounted upon a retractable axle 21 supported upon tape head frame 1. The tape head frame

30 1 is comprised of two parallel spaced members (1 and 1') supported at opposite ends upon the revolvable spider frame 2. Elements 22 and 23 carry the pad friction means 7 and 7' and are adapted to be adjusted along the longitudinal axis of the axle 21 so as to bring the pad center line A to a desired position between the tape head frame 1 and 1'. The retractable axle 21 is provided with a handle 24 to provide means to withdraw the axle from the position shown to 40 allow pad 5 to be inserted into the position shown. Means 26 is provided to lock the axle 21 from rotating.

Spring tension means 25 insures that element 22 is pressing towards the pad center thus bringing friction ring 15 and spring fingers 13 against the pad side.

We prefer to fixedly position element 23 carrying pad friction means 7 and to fixedly position friction disk 15' thereupon. Coil springs 16, 50 therefore, are only provided for friction disk 15 as this reduces the possibility of lateral side play in tape pad 5 as it is revolved about its center axis.

The planetary taping machine shown and described herein is adapted for rotation of the taping head in either clockwise or counterclockwise directions, it merely being necessary to adjust guide roller 11 to the proper position to supply the tape 5' on the proper side of the cable 4. It is also adapted to wrap a plurality of tape sizes 60 upon the cable 4 without material adjustment in the tape roll supporting means. Another advantage is that the size of the machine can be greatly reduced due to the use of the caster type guide roller. Still another advantage lies in the 65 exact control over the tension of the wrapping as it is laid upon the cable through the use of the tape tension means disclosed. As the tape tensioning means operates effectively within relatively wide ranges of planetary revolution speeds and the caster roller guide means functions within relatively wide ranges of cable longitudinal advance speeds, the flexibility and adaptability of the machine to modern high speed production requirements is marked.

75 As an added improvement means 30 may be

provided on the taping head disposed at a determined point to disconnect the driving means for the wrapping machine when and in the event that the tape 5' is broken or the end of a tape passes the means 30 before a new tape roll is inserted. 5 Means 30 may be of any convenient type and as shown in Fig. 3 comprises a lever arm 31-32 pivoted at point 30, one arm (31) being adapted to be engaged by pin 33. When tape 5' is passing over roller 10, spring 37 is compressed, thereby 10 allowing arm 32 to be held in the open position by spring 34. When the tape 5' breaks or the end passes over drum 8 spring tension means 37 is released and moves roller 10, pin 33 and arm 31 to the right causing lever arm 32 to compress 15 spring 34 and engage with spring terminal 35 connected to lead wire 36 and closing an electrical relay circuit which operates to disconnect the power supply to the wrapping machine and stop same. Means 30 may be positioned at the point 20 shown or at any other convenient point on the taping head 1.

Having broadly and specifically described the present invention, it is believed apparent that many modifications and departures may be made 25 therein without departing essentially from the nature and scope of the same, and such modifications and departures are anticipated as may fall within the scope of the following claims.

We claim:

1. In a cable wrapping machine of the planetary type, means to sustain a cable in a straight-away course, means to sustain a plurality of taping heads spirally about and adjacent said course, means to support a tape roll on each taping head 35 said means providing means to permit the roll to rotate freely about an axis parallel to the longitudinal axis of the said cable, means to impart a desired and substantially constant friction opposing the rotation of said roll about said axis irrespective of the diameter of said roll, and means to lead tape from said roll to the said cable, said means including guide means to lay the tape upon the cable substantially free from lateral restraint and tape tensioning means to impart a substantially constant and desired tension in the tape as it is laid on said cable. 40

2. In cable wrapping machines of the type described and claimed in claim 1, means to support a tape roll upon a taping head, said means including a hollow centered anti-friction bearing hub member adapted to be disposed at the center axis of the roll, an axle adapted to be received in said bearing, means to retractably support said axle upon the taping head with its longitudinal axis in a plane substantially parallel to the longitudinal axis of the cable, means to lock the axle from rotation, means to frictionally engage the sides of a pad roll mounted on said axle throughout its entire radius and means to adjustably position the side friction means to permit the mounting of tape rolls of varying widths on said axle. 55

3. In cable wrapping machines of the type described and claimed in claim 1, means to impart a substantially constant tension to the tape unwinding from said tape roll, said means including a pair of parallel spaced arms radiating from the axle supporting means at an angle substantially perpendicular to the longitudinal axis of said axle and adjacent the said tape roll, each of 60 said arms carrying means to frictionally engage the side faces of said tape roll throughout its entire radius from its maximum to minimum diameter, the degree of said frictional engagement being adapted to maintain substantially constant 70

- tension in the unwinding tape from maximum to minimum diameter of tape roll.
4. In cable wrapping machines of the type described and claimed in claim 1, means to impart a substantially constant and desired tension in the tape as it is laid upon the cable, said means comprising a non-slipping friction drum intermediate the tape roll and the cable over which the unwinding tape is passed, and electrically controlled braking means therefor.
5. In cable wrapping machines of the type described and claimed in claim 1, guide means to lay the tape upon the cable substantially free from lateral restraint, said means comprising a roller sustained adjacent the cable course and rotatable with the taping head, said roller being supported with its longitudinal rotating axis disposed in a plane substantially parallel to the longitudinal axis of the said cable, the supporting means for said roller being adapted to permit the roller to rotate about its transverse axis in a plane at right angles to its longitudinal axis and in a plane adapted to maintain the center axis of tape passing thereover to the cable in a plane at substantial right angles to the center axis of the tape approaching the roller from the tape tensioning means of said wrapping machine, a second roller intermediate the first roller and the tape tensioning means around which the tape passes before reaching the first roller, the longitudinal rotating axis of said second roller lying in a plane substantially parallel to the said first roller and spaced therefrom a determined distance.
6. In cable wrapping machines of the type described and claimed in claim 1, pad friction means for tape roll, said means comprising a pair of parallel spaced arms radiating from the tape roll supporting means on opposite sides of the roll, a plurality of spring finger members supported thereon and adapted to frictionally engage the sides of the roll along its entire radius, friction ring members disposed at the axial center of said roll and adapted to frictionally engage the sides of the roll throughout an extended area, adjustable spring tension means on at least one of said ring members to control the extent of the frictional engagement of said ring members at the roll center, and means to adjustably position said arms to permit the insertion of tape rolls of varying widths therebetween.
7. In a cable wrapping machine of the planetary type, means to sustain a cable in a straight-away course, means to sustain a plurality of taping heads spirally about and adjacent said course, means to support a tape roll on each taping head said means providing means to permit the roll to rotate freely about an axis parallel to the longitudinal axis of the said cable, means to impart a desired and substantially constant friction opposing the rotation of said roll about said axis irrespective of the diameter of said roll, and means to lead tape from said roll to the said cable, said means including guide means to lay the tape upon the cable substantially free from lateral restraint and an electrically controlled tape tensioning means to impart a substantially constant and desired tension in the tape as it is laid on said cable.
8. In a cable wrapping machine of the planetary type, means to sustain a cable in a straight-away course, means to sustain a plurality of taping heads spirally about and adjacent said course, means to support a tape roll on each taping head said means providing means to permit the roll to rotate freely about an axis parallel to the longitudinal axis of the said cable, means to impart a desired and substantially constant friction opposing the rotation of said roll about said axis irrespective of the diameter of said roll, and means to lead tape from said roll to the said cable, said means including guide means to lay the tape upon the cable substantially free from lateral restraint and an electrically controlled tape tensioning means to impart a substantially constant and desired tension in the tape as it is laid on said cable, and means to automatically disconnect the power supply to the driving means of the wrapping machine when a tape end passes a determined point on said taping heads.

STANLEY F. FRENCH.
ERNEST L. JUNGHANNS.
